PORTABLE OUTDOOR COOKER

Billy Gene Jones, Tallahassee, Fla.

Application December 15, 1958, Serial No. 53,769

Term of patent 14 years

(Cl. D81—10)

Fig. 1

Fig. 2

Fig. 3

Fig. 4

Fig. 5

Fig. 7

Fig. 6

Fig. 1 is a perspective view looking downwardly at the front and right side of a portable outdoor cooker embodying this design, the cooker being compactly folded into an easily portable carrying position.

Fig. 2 is a rear plan view thereof showing the cooker positioned for cooking.

Fig. 3 is a perspective view looking downwardly at the front and right side thereof and showing the cooker positioned for cooking.

Fig. 4 is a top plan thereof showing the cooker positioned for cooking.

Fig. 5 is a longitudinal sectional view taken substantially on the line 5-5 of Fig. 4.

Fig. 6 is a perspective view in open position, of a

modified form of the portable outdoor cooker disclosed in Figs. 1 to 5, inclusive.

Fig. 7 is a longitudinal sectional view taken substantially on the line 7-7 of Fig. 6.

I claim:

The ornamental design for a portable outdoor cooker, as shown and described.
